METAL AWNING

Florian G. Dueweke, Detroit, Mich.

Application May 24, 1940, Serial No. 336,971

4 Claims. (Cl. 156—44)

The present invention pertains to new and useful improvements in an awning structure.

The invention embodies utilitarian features in that owing to the entire structure being formed of metal, certain desirable conditions conducive to fire prevention are apparent.

It is an object of my invention to provide an awning structure so constructed and arranged as to afford adequate protection against nature's elements, wind, rain and sunshine, while also serving to beautify dwellings and buildings.

Another object of the invention is in the provision of an awning structure of fire resisting material, that may be raised or lowered with ample ease.

A further object of the invention is to provide an awning structure that may remain affixed to a building throughout an entire season, obviating seasonal installations.

Still a further object is to so arrange and construct parts as to provide a simple awning structure having ease of operation and being economical of manufacture.

Other objects will appear hereinafter.

The invention can best be interpreted by reference to the appended drawing, which forms a part of this specification, with similar reference numerals referring to similar parts throughout the several views and in which:

Fig. 1 is a front elevational view of the awning structure secured to a conventional window, with parts of the frame broken away, the awning being in raised position;

Fig. 2 is a side elevational view of the invention with the window casement in section, and the awning shown in an intermediate position in dotted lines;

Fig. 3 is an enlarged fragmentary view of the awning and supporting rod with parts broken away;

Fig. 4 is a plan view taken upon line 4—4 of Fig. 3, with parts broken away;

Fig. 5 is a sectional view taken along line 5—5 of Fig. 3;

Fig. 6 is an enlarged side elevational view of the supporting arms in their relation, when the awning is in lowered position;

Fig. 7 is a bottom plan view of the structure shown in Fig. 6; and

Fig. 8 is an elevational view taken upon line 8—8 of Fig. 1.

The invention is shown mounted upon a conventional window casement 3, provided with the upper and lower sashes 5 and 7 slidable therein. The awning structure is attached to the upper

section 9 of the window casement by a semi-circular housing 11 having right angle flanges 13 thru which project fastening screws 15 into the window casement. The housing is formed with end walls 17 into which are suitably journalled stub shafts 19 and 21 at the respective ends of a roll 20 therein. Upon this roll a flexible metal shade 41 is adapted to be rolled, one end thereof being attached to said roll.

The shaft 19 terminates in the side wall of the housing. The shaft 21 has a collar 23 upon the inner side of the side wall, and continues therethrough, having a sprocket wheel 25 fixedly mounted thereon, the shaft extending into a suitable journal or bracket 27, affixed to the aforementioned flange 13 on the housing.

The awning structure proper is constructed of a frame having a horizontal lower member 29 and vertical side-members 31 which, at their upper ends, are swingably mounted on pins 33 in the end walls 17 of the housing, permitting the frame to be swung into an angularly raised position or into a lowered position against the window casement. Each of the side members is so constructed as to form a track, each side member having a right angular flanged portion 35 along its outer side, and each, upon its inner side, has a parallel member 37 spaced therefrom. Sound insulating material 39, such as felt, may be positioned therebetween to accommodate the flexible metal shade 41, adapted to slide therein.

The frame as described thus far is maintained in its respective positions, i. e. parallel or angular to the window casement by means of a pair of arms. Each arm consists of two sections 43 and 45, each section 43 being pivoted in a bracket 41, one mounted upon each outer side of the window casement. Each section 43 is connected to a section 45 by a pivot 49. The outer end of section 45 of each arm is swingably mounted upon a pin 51, adapted to slide in a slot 53, one slot being formed in each of the side members 31 of the frame.

U-shaped retention springs 55 bear against the periphery of the pivot pins 49 with one end adapted to apply spring pressure against the inner side of the flange 44 of the arm section 43, with the other end received in a groove 57 in the arm section 45, normally urging the respective arm sections into parallel axial relation to one another.

Referring to Fig. 1 it will be noted that the awning, or flexible shade 41, is shown in a raised position, admitting clear, unobstructed vision

thru the window sashes 5 and 7 in the casement.

The metal shade or awning is raised or lowered to its respective positions thru suitable means here shown as comprising a handle 59, mounted conveniently upon the inside of the casement and journalled therein as at 61, with an extension shaft 63 protruding beyond the outer side of the casement and having a gear or sprocket wheel 64 keyed thereon for rotation therewith, with a cooperating endless chain 65 having its other end passing around the periphery of the aforementioned gear 25 upon the shaft 21, and passing over an idler or guide sprocket 66 of smaller diameter for rotation of the shade roll.

The flexible shade 41 slides in the track-like groove formed by the flanges 35 and 37 and is retained therein by a transverse supporting bar 67, around which one end of the shade 41 is secured.

A pair of chains 69 are so positioned on the inner side of the side members 31, each having one end thereof attached to the transverse bar 67 of the shade 41, and the other end secured to the pivot pin 49, journalled in the arms 43 and 45, that upon rotation of the shade-rolls 23 in a direction to raise the shade 41 from the lowered position as partly shown in Fig. 3 to the raised position shown in Fig. 1, first the retention spring will yield and then the pairs of arms will assume a position as indicated by the dotted lines in Fig. 2 and subsequently fold parallel and adjacent one another into a closed position of the awning frame structure as shown in full lines in Fig. 2.

Operation

As shown in Fig. 1 the shade is in its raised position and the frame proper is in parallel adjacent relation with the casement.

Upon rotation of the handle inside the casement by the operator, the sprocket and chain means will rotate the shade roll, effecting a lowering of the shade in its track, and the pin 51 in arm 45 will descend until it reaches the bottom of the slot 53. At this point the retention springs will endeavor to return to a normal relaxed position, effecting the lowered position of the entire awning structure.

Aside from the specific embodiment of the invention herein shown and described, it will be understood that numerous details of the construction may be altered or omitted without departing from the spirit and scope of the invention as disclosed and claimed, and that I do not desire to limit the invention to the exact construction herein set forth.

I claim:

1. In combination in an awning, a roll, support means for rotatively journalling said roll, means for rotating said roll, a flexible shade connected to and adapted to be rolled upon said roll, side members pivoted at their upper ends adjacent the ends of the roll, said side members having opposed guide means forming tracks in which the opposite edges of the flexible shade are

adapted to slide, and means connected to the shade for simultaneously inclining the side members to awning shade supporting position upon unreeling the flexible shade from the roll and sliding it in said tracks.

2. An awning comprising, a roll, support means for rotatively journalling said roll, means for rotating said roll, a flexible shade connected to and adapted to be rolled upon said roll, side members pivoted at their upper ends adjacent the ends of the roll, said side members providing opposed guide means forming tracks in which the opposite edges of the flexible shade are adapted to slide, and means connected to the shade for lowering the side members from awning shade supporting position as the flexible shade is reeled upon the roll.

3. In combination in an awning, a roll, support means for rotatively journalling said roll, a flexible shade having its upper end connected to said roll, a frame having side members pivoted at their upper ends adjacent the ends of the roll, said side members having opposed guide means forming tracks in which the opposite edges of the flexible shade are adapted to slide, a pair of foldable and swingable arms adapted to be pivoted at one end to a building wall on opposite sides of an opening, each of said arms comprising two sections, pivotal joint connecting means for joining the adjacent ends of said arms' sections, resilient means adapted to normally force said arms from folded to extended or opened position, slack motion means joining the lower ends of said arms to the frame side members, means for rotating the roll, and means connecting the pivotal joint connecting means of the foldable arm sections to the flexible shade whereby, reeling up the shade on the roll causes the arm sections of each arm to fold toward each other, thus lowering the frame to the opening, and unreeling of the shade permits the resilient means to force the arm sections into open or extended position, thus forcing the frame outwardly into a shade supporting position.

4. An awning having in combination, a roll, support means for rotatively journalling said roll, a flexible shade connected to and adapted to be rolled upon said roll, side members pivoted at their upper ends adjacent the ends of the roll, said side members having opposed guide means forming tracks in which the flexible shade is adapted to slide, a pair of arms, each being adapted for pivotal connection at one end to a building wall, one on each side of an opening, each of said arms comprising two sections adapted to be folded toward each other, a pivotal connection for each pair of arm sections, resilient means adapted to normally force said arm sections of each arm into axial alignment, longitudinal slots in the lower ends of the side members, a projection on the outer end of each arm adapted to slide in the slot of its adjacent side member, flexible means connecting the end of the flexible shade remote from the roll to the pivotal connection of the arm sections, and means for rotating the roll.

FLORIAN G. DUEWEKE
